MILL FOR GRINDING COCOA

Filed July 22, 1925

Fig.1.

UNITED STATES PATENT OFFICE

OTTO THURMANN, OF BERLIN, GERMANY

MILL FOR GRINDING COCOA

Application filed July 22, 1925, Serial No. 45,174, and in Germany December 31, 1924.

This invention relates to a mill for grinding cocoa, chocolate and like substances in a liquid, paste-like state, which is constituted by a combination of a rough grinding mill with several ball mills for fine grinding and is so arranged that the material ground is discharged from it in a completely finished state provided with all admixtures such as sugar, etc.

10 A construction of the mill according to this invention is shown in Figure 1 of the drawings in a vertical axial section, in Figure 2 in plan, with the runner parts partly broken off and in Figure 3 which shows a piece of a

15 ring part.

1 is a fixed grinding cone arranged with the point upwards and provided with grooves, such as shown in Figure 2. A correspondingly shaped hollow cone 2 with similar grooves on the inner surface forms the runner, and is driven from the vertical spindle 3 passing through the fixed grinding cone 1. The fixed grinding cone 1 is concentrically surrounded by two annular or ring

20 channels 4 and 5 of about semi-circular cross-section in such a manner that the outer channel 5 is at a lower level than the inner one 4. In each of these annular channels runs a number of balls 6, 7. The balls 6 are covered by a movable runner cover 8 having the form of an annular channel and preferably made in one piece with the cone 2. The cross-section of this cover is also semi-circular, and makes with the cross section of the fixed channel 4 a circle, of which the balls fill up the cross section. The same applies to the balls 7 which are covered by a runner cover 9, also of the form of an annular channel.

25 The runner covers 8 and 9 are not connected together in any way, so that the runner cover 8 alone loads or presses on the balls 6, and the runner cover 9 alone loads or presses on the balls 7. The runner cover 8 is provided on its upper face with annular walls 10, 11 which form a chamber above it, intended to receive loading weights 12, 13. In the same way, the runner cover 9 is provided with annular walls 14, 15 for receiving the loading weights 16, 17. The movement is transmitted to the runner cover 8 through the run-

ner cone 2 to which it is secured, and to the runner cover 9 by the runner cover 8 through a spring 18 which is attached at one end to an arm 19 of the runner cover 8, and at the other end to a projection 20 of the annular wall 15 of the runner cover 9. Obviously, several such springs may be used.

Owing to this arrangement, the grinding pressure in each ball ring is regulated as desired, and the resistances to which one ball ring is exposed, do not affect the grinding work of the other ball ring. Further the grinding of the cocoa may be effected by the first ball ring alone, and only then, in passing the material into the outer ball ring, to add the sugar through the upwardly divergent slot between the runner covers 8 and 9, and to grind it together with the cocoa by means of the outer ball ring, so that the material is discharged from the mill as finished chocolate. Obviously further ball rings may be arranged round the existing ones, and this outer grinding ring may be driven in any desired manner without any connection with the drive from the centre.

To prevent the balls from striking each other and subsequently becoming distributed irregularly, and further to ensure an exact discharge of the ground material, the following arrangement is adopted.

30 Each of the two ring channels 6 and 7 is surrounded by a ring 21 provided with semi-circular recesses 22 fitting the balls. These rings are mounted in suitable milled recesses of the annular channel bodies 4 and 5 and rotate in them round the spindle 3 when the balls roll during the grinding in the annular channels 6 and 7. The upper surface of the rings 21 is about on the level of the centres of the balls, so that during the rolling, the cocoa or chocolate adhering to the balls is stripped off and runs from the rings outwards, so that it passes either from the annular channel 4 into the channel 5, or from the annular channel 5 into the outer collector channel 23.

Having now particularly described and ascertained the nature of my said invention and in what manner the same is to be performed, I declare that what I claim is:

1. A mill for grinding cocoa, chocolate and the like, consisting of a number of individual grinding devices, concentrically arranged, and having fixed grinding surfaces below and movable grinding bodies above, of which grinding devices the center one is a rough grinding mill and the outer ones are ring-shaped balls with weight lids, the organization being such that each of the movable upper parts is driven by the movable upper part of the next inner ring yet receives no pressure therefrom in the direction perpendicular to the milling surface, said mill having the characteristic that between the lower and the upper part of the grinding ball rings there are loosely movable annular plane plates, which plates are provided on their inner side with semi-circular recesses to receive the balls and guide them and strip off the ground material from them.
2. A mill for grinding cocoa, chocolate and the like, consisting of a number of individual grinding devices, concentrically arranged, and having fixed grinding surfaces below and movable grinding bodies above, of which grinding devices the center one is a rough grinding mill and the outer ones are ring-shaped balls with weight lids, the organization being such that each of the movable upper parts is driven by the movable upper part of the next inner ring yet receives no pressure therefrom in the direction perpendicular to the milling surface, said mill having the characteristics that springs are used to convey the movement from one movable upper grinding body to the next and that between the lower and the upper part of the grinding ball rings there are movable annular plates set about the common spindle, which plates are provided on their inner side with semi-circular recesses to receive the balls and which guide the balls and strip off the ground material from them.
3. A mill comprising a plurality of ball grinding devices disposed concentrically and having the characteristic feature that the grinding cover of each individual one of the grinding devices comprises means constructed to receive additional weighting members, each independently of the other, by additional weights that may be put on them.
4. A mill comprising a plurality of ball grinding devices disposed concentrically and having the characteristic feature that the innermost grinding device is moved directly by the mill axle whereas the grinding ring cover of the other grinding devices is connected up in the direction of movement with the innermost grinding device, by means of drawing-springs, in an elastic manner.

In testimony whereof I have signed my name to this specification.

OTTO THURMANN.
